CLAIM

The ornamental design for a shoe, as shown and described.

DESCRIPTION

FIG. 1 is a rear, right, top perspective view of a shoe, showing my new design;

FIG. 2 is a rear, right, bottom perspective view thereof;

FIG. 3 is a front, left, top perspective view thereof;

FIG. 4 is a front, top perspective view thereof;

FIG. 5 is a right side view thereof;

FIG. 6 is a left side view thereof;

FIG. 7 is a front view thereof;

FIG. 8 is a rear view thereof;

FIG. 9 is a top view thereof;

FIG. 10 is a bottom view thereof;

FIG. 11 is an enlarged detail view of "11" in FIG. 1;

FIG. 12 is an enlarged detail view of "12" in FIG. 1;

FIG. 13 is an enlarged detail view of "13" in FIG. 2;

FIG. 14 is an enlarged detail view of "14" in FIG. 2;

FIG. 15 is an enlarged detail view of "15" in FIG. 3;

FIG. 16 is an enlarged detail view of "16" in FIG. 4;

FIG. 17 is an enlarged detail view of "17" in FIG. 6;

FIG. 18 is an enlarged detail view of "18" in FIG. 7;

FIG. 19 is an enlarged detail view of "19" in FIG. 7;

FIG. 20 is an enlarged detail view of "20" in FIG. 8;

FIG. 21 is an enlarged detail view of "21" in FIG. 8;

FIG. 22 is an enlarged detail view of "22" in FIG. 8;

FIG. 23 is an enlarged detail view of "23" in FIG. 9;

FIG. 24 is an enlarged detail view of "24" in FIG. 9;

FIG. 25 is an enlarged detail view of "25" in FIG. 10; and,

FIG. 26 is an enlarged detail view of "26" in FIG. 10.

The dashed broken lines in the figures are for the purposes of illustrating portions of the shoe and form no part of the claimed design.

The short-short-long dashed broken lines immediately adjacent to the claimed areas in the views represent the boundaries of the design and form no part of the claimed design. The dash-dot-dash broken lines are for notating enlarged views and form no part of the claimed design.
